STOVEPIPE ANCHOR AND LOCK

Filed Dec. 8, 1923

Fig. 1.

Charles Wade.

R. E. Wade.

WITNESS:

INVENTOR
BY Victor J. Evans

ATTORNEY

UNITED STATES PATENT OFFICE.

CHARLES WADE, OF SAGINAW, MICHIGAN.

STOVEPIPE ANCHOR AND LOCK.

Application filed December 8, 1923. Serial No. 679,442.

To all whom it may concern:

Be it known that I, CHARLES WADE, a citizen of the United States, residing at Saginaw, in the county of Saginaw and 5 State of Michigan, have invented new and useful Improvements in Stovepipe Anchors and Locks, of which the following is a specification.

The object of this invention is to provide 10 a thimble adapted to be built into a chimney and anchored, the thimble being formed with a portion cooperating with a lug on the pipe entering the chimney, and the lug being engaged by a locking element, so that 15 there is no possibility of accidental separation, and no danger of fire from this cause.

With the foregoing and other objects in view, the invention consists in the novel construction and arrangement of elements described 20 illustrated and claimed, it being understood that modifications may be made within the scope of the claims without departing from the spirit of the invention.

In the drawings, Figure 1 shows a pipe 25 thimble and portion of a chimney in section, and the end of a stove pipe locked in position; Figure 2 is an end elevation of the thimble, in position in the chimney; Figure 3 is a side elevation of the thimble; Figure 30 4 is a fragmentary perspective view, the locking elements being detached.

The main cylindrical portion 10 of the pipe thimble corresponds in length with the thickness of the wall of the chimney, a 35 portion of the latter being designated 11. An inner flange 12 may be cut away at 13 and 14 and the distance between the cut away portions is equal to the width of the flue on the inner side.

40 A flange 15 on the inner end of element 10 takes the place of the usual pipe collar, and is provided with a rounded portion 16, the flat portion 17 being in contact with the masonry or the plaster finish thereon.

A section of pipe is designated 18, and a 45 lug 19 secured thereto enters a recess 20 formed in the thimble—the recess constituting a groove in the inner wall. A slot or opening 21 communicates with the recess and extends radially of the thimble, providing for the insertion of a key 22 for engaging the lug 19 and preventing accidental displacement of the pipe.

The thimble may be made of iron or other suitable material of sufficient strength to 55 permit it to constitute a reinforcement when built into the structure, with the flanges surrounding the edges of the flue opening 11' in the manner indicated.

What I claim is:

1. In a device of the class described, a pipe thimble comprising a cylindrical portion having flanges on opposite ends thereof, said thimble having a recess opening toward the bore of the thimble, a pipe projecting 65 into the thimble, a locking element carried by the pipe, said element entering the recess, and means for retaining the locking element in position.

2. In a device of the class described, a pipe 70 thimble comprising a cylindrical portion having flanges on opposite ends thereof, said thimble being formed with a recess communicating with the bore of the thimble, a pipe projecting into the thimble, a lug carried by the pipe and located in the recess, and a key passing through a portion of the thimble and engaging the lug.

3. The combination with a thimble having 75 a flange, the flange having a recess therein, of a pipe projecting into the thimble and a lug thereon, said lug being located in the recess, the flange having an opening extending radially of the thimble, and a key entering the opening and engaging the lug.

CHARLES WADE.
